INVENTOR.
ALBERT. F. DAYTON

MUNN & CO. ATTORNEYS.

UNITED STATES PATENT OFFICE.

ALBERT F. DAYTON, OF PLEASANTON, CALIFORNIA.

VAPORIZER.

Application filed August 13, 1923. Serial No. 657,257.

To all whom it may concern:

Be it known that I, ALBERT F. DAYTON, a citizen of the United States, and a resident of Pleasanton, county of Alameda, State of California, have invented a new and useful Vaporizer, of which the following is a specification.

This invention relates to vaporizers for liquid fuel burners and particularly to burners designed for use in connection with steam-driven automobiles or other vehicles, and has for its primary object the provision of a device of this character which can be easily and quickly cleaned as the occasion requires.

A further object of the invention is to provide a vaporizer of this character which will operate to maximize vaporization of the fuel before it reaches the burners of the heating system with which it is employed, and to so construct and design the invention whereby a vaporizing area of maximum proportion may be arranged in a space of minimum size.

Another object of the invention is to provide a vaporizer whose characterizing features act to insure perfect vaporization of the fuel and to accommodate an excess supply of gas and permit said supply to be drawn upon in a manner to induce and maintain steady pressure on the burner nozzles and a flame of uniform size.

Another object of the invention resides in the provision of a vaporizer which can be entirely removed from its co-acting burners and boiler structures respectively and instantly reapplied thereto so that the vaporizer may be always kept in a clean working condition, free from carbon deposits which would otherwise act to clog the device and prevent the free flow of gas to the burners.

A still further object of the invention is to provide a vaporizer that can be quickly arranged in a liquid fuel burning system of well-known design and which, when necessary, can be removed from the system and a new vaporizer substituted therefor at small cost and without requiring the skill of an expert mechanic.

My invention, therefore, comprises certain novel features of construction and arrangement and combination of elements hereinafter set forth and pointed out in the claims annexed hereto.

In the drawings, Figure 1 is a perspective view of the vaporizer, Figure 2 is a vertical longitudinal section therethrough showing its application to a fire-box, and Figure 3 is a transverse section taken on the line 3—3 of Figure 2.

As herein stated, my invention is particularly designed for use in connection with liquid fuel operated vehicles of the steam driven type. This, however, is simply illustrative and shall not be taken as an unnecessary limitation of the invention as it is capable of being used in connection with any well-known form of fuel burner. I mention its particular adaptability to mechanisms of the above mentioned type because of the ease with which the vaporizer can be removed when it is desired to clean same of carbon deposits or foreign sediment. Its design peculiarly adapts itself to steam-driven vehicles because of the dispatch with which the invention can be removed as desired without requiring the aid or assistance of a skilled mechanic, and further because of the facility with which the invention can be removed as the occasion requires and later readjusted to the burner system without in the least way impairing the latter.

I will therefore refer to A as a conventional fire-box of the type employed in connection with the boiler of a steam engine. This fire-box is provided with a fuel vaporizer (5) which includes in its construction an outer tube or pipe (6) and an inner tube (7). The outer tube extends through the fire-box and beyond the sides thereof and one end of the tube is closed by a removable cap (8). On the outside wall of the box and in contact therewith is a stop shoulder (9) formed as a fixed part of said tube (6). The opposite end of the tube is connected with a fuel inlet pipe (10) which leads from a source of supply, not shown. Generally this source of supply includes means whereby liquid fuel under suitable pressure may be fed to the burners of a heating system. In the present instance, liquid fuel from the supply is conducted to the tube (6). The tube is disposed in the fire-box so that it is made to overlie the usual burners. It acts in the fashion or manner of an overlying retort and is so subjected to the action or heat of the flame as to cause proper vaporization

of the oil as the latter is fed from its source of supply.

The inner tube (7) is preferably formed of copper or other suitable heat-retaining material and as illustrated this tube is closed at one end as at (11) and open at its other end (12). This provides the tube with a gas chamber wherein excess gas may be accommodated to insure a steady condition 10 of the flame at the burners. This chamber acts to establish a reserve for the gas and according to operations of the burners this reserve can be drawn upon with consistency and to the extent that a uniform pressure is 15 maintained at the burners. One end of the tube (7) faces in the direction of cap (8) and same is formed with an internal thread (13). When it is desired to remove the tube (7) or core, so to speak, the cap (8) 20 is taken off of the outer tube (6) and a suitable tool or threaded rod, not shown, is inserted in said tube (6) and manipulated so as to cause it to engage with the aforesaid thread (13). By drawing in an outward 25 direction upon the tool, the said tube (7) will be withdrawn therewith. It can then be immersed in a cleansing bath, such as gasoline or the like, or scrubbed or otherwise suitably washed in order that sediment, 30 sand and carbon deposits can be removed therefrom. When this is accomplished the said tube (7) can be readjusted to its former position. All of this may be accomplished with dispatch and with utmost ease 35 and convenience.

In order that the fuel, as it enters the tube (6) may be made to take maximum travel around the tube (7) or between same and the outer tube (6), and further with a 40 view of thoroughly disintegrating the fuel, I provide said tube (7) with an external spiral thread (14). This extends preferably throughout the length of the tube and the windings of the thread or convolutions are 45 proportioned to come snugly in engagement with the inner walls of the tube (6). In this manner and according to the precise spacing apart of the windings of the thread (14) I am able to cause a maximum circulation of liquid fuel over a minimum area 50 and at the same time insure proper vaporization of the fuel before it is delivered as a gas to the burners.

The outer tube (6) is provided with a hollow head (15) arranged in open communication with the tube (6) by way of the perforations (16). This head supports pipes (17) from which the usual burners (18) are hung. These burners extend into the 60 fire-box so that the flame produced thereby

will be made to impinge against the vaporizer.

From the foregoing description it obviously follows that a novel form of vaporizer is provided wherein the parts thereof are freely separable in order that these parts may be set up or knocked down as the occasion requires, and that these parts are so designed and constructed that they may be conveniently installed in the fire-box of a burner system without requiring any elaborate or costly alteration in the construction thereof.

I claim:

1. A vaporizer comprising an outer tube 75 provided with a removable cap at one end and a liquid fuel intake at its opposite end, burners in communication with said tube and a mixer in said tube, said mixer being freely removable from the tube when 80 said cap is removed, a spiral thread formed on the mixer and arranged with its windings in close engagement with the inner walls of said tube, the said tube being open at one end and closed at its other end so as to constitute a gas retaining chamber.

2. A vaporizer comprising a tube closed at one end by a removable cap and provided at its other end with means for the introduction to the tube of liquid fuel, and a hollow mixer arranged in the tube and provided with an open end in juxtaposition to the cap and a closed end facing the fuel intake end of said tube.

3. A vaporizer comprising a straight tube 95 provided with a removable closure at one end and means at its opposite end for introducing liquid fuel to the tube, and a hollow tubular mixer removably mounted in said tube, said mixer being closed at one end 100 and open at the other and provided with external means embraced by the walls of the tube for defining therewith a fuel circulating channel, and means on the tube for arranging a burner in open communication 105 therewith.

4. A vaporizer comprising a tube having an inlet for the introduction of liquid fuel to the tube and an outlet for the discharge of gas from the tube, a hollow cylindrical mixer in said tube, said mixer being closed at its end adjacent to the fuel intake of the tube and open at its end adjacent to the fuel outlet of said tube and provided with an external thread embraced by the walls of 115 the tube to constitute therewith a mixing chamber and circulating space around the mixer.

ALBERT F. DAYTON.
